INDEX RECKONER CALENDAR

Filed April 24, 1922

2 Sheets-Sheet 2

UNITED STATES PATENT OFFICE.

JOHN H. KULOW, OF BUFFALO, NEW YORK.

INDEX RECKONER CALENDAR.

Application filed April 24, 1922. Serial No. 556,300.

To all whom it may concern:

Be it known that I, JOHN H. KULOW, a citizen of the United States, residing at Buffalo, in the county of Erie and State of New York, have invented certain new and useful Improvements in Index Reckoner Calendars, of which the following is a specification.

Primarily my invention has for its purpose to provide an index reckoner calendar designed for useful and ornamental application, either as a calendar per se, or for attachment to other articles of manufacture such, for example, as a base or supporting member that is particularly adapted and designed for advertising purposes or works of art.

More specifically my invention comprises a new and novel construction of index reckoner calendar in which the calendar faces are designed to present the usual month and day indicia and indexed to designate the number of days leading from any selected date on the calendar in reverse direction, that is, commencing with "1" on January 1st of the year and ending with "365" December 31st of that year or reversely beginning with "1" December 31st and to the end "365" on January 1st of such year or in other words, each calendar sheet is designed for designating at a glance, when turning the sheet to select any particular day of the year the number of the days of the year that have passed from January 1st to such date and how many days of the year remain between such selected day and the end December 31st of the said year, the arrangement of the indicia on the face of each calendar sheet, providing, as it were, a ready reckoner in determining the intervening days between any given period reading either forwardly from the beginning or reversely from the end of the year.

A still further object of my invention is to provide, in a calendar of the general character stated, an improved construction of date pad, that is, a series of monthly calendar sheets, so arranged that the indexing of the pad sheets is materially simplified, is capable of being more quickly and accurately read, than by the usual edge indexing tabs, and by which provision is made on the successively readable month sheets (reading from February down), owing to progressively increasing blank spaces left at the top

or head portions of the calendar sheets, for the placing of advertisements or ornaments, the said spaces, when they are to be utilized for receiving advertisements, progressively increasing in value, due to the gradual increasing blank areas left at the tops of the aforesaid progressively arranged calendar sheets, as indicated in Figure 5 of the drawing.

In its complete form, my invention comprehends the provision of a pad of calendar sheets and a suitable base or pad, preferably of card-board, that may be designed, either to represent a work of art, or to be useful for advertising purposes and which has special provision for holding the calendar sheets to their turned back position, as the month for which they are particularly provided ends, to thereby keep the pad sheets for the complete year together, so that, when it may be desired to calculate time of days from a certain past date to another period, in either the forward or reverse direction from the selected date, the pad sheets can be conveniently brought into position for gathering the data desired and as readily returned to the turned back position to keep the current month calendar sheet in view.

With the above in view, and other minor objects that will be hereinafter incidentally mentioned, my invention is a combined calendar and advertising media of the general character stated that embodies the peculiar features and novel arrangement of parts, all of which will be herein-after fully explained, specifically pointed out in the appended claims and illustrated in the accompanying drawings, in which:

Figure 1 is a front view of the preferable arrangement of my combined index reckoner and advertising calendar.

Figure 2 is a similar view which illustrates all the month calendar sheets, down to the March sheet, bent back, one corner of the said March sheet being bent back to illustrate a portion of the April calendar sheet below it, a slight modification of the arrangement of the lettering being also shown.

Figure 3 is a vertical transverse section of the complete calendar form shown in Figure 2 and taken substantially on the line 3-3 of Figure 2.

Figure 4 is a perspective view of the card board base, with which my calendar pads

are combined in the complete application of my improved index reckoner calendar, the upper and lower sections of the base and the spring clip device being shown 5 separated.

Figure 5 is a face view of a modified arrangement of a calendar pad, in which is embodied my invention.

In the practical application of my invention, when the same is applied as shown in the accompanying drawings, the calendar pad or sheets are mounted on a base of any suitable material, preferably, on account of economy of manufacture and lightness, of 10 stiff card board.

I make the base of three members, a lower cardboard section 1 and an upper card board section 2, which sections are secured together by a resilient or spring device 3, 15 the construction and the purpose of which will be presently explained.

The two card board sections are fixedly connected in the completed structure, and the lower section 1, in the upper edge and 20 centrally thereof, has a notch 10 which is of sufficient width in the manufacture of the base for at once placing the spring in operative position.

The lower and upper base sections 1 and 2, 25 when the calendar parts are finally assembled, are glued along the line 5, as indicated in the drawings, and the rigid joining of the said sections causes the upper section to function with the spring device 3 in receiving 30 or releasing the bent back matured month sheets of the date pad, as will hereinafter be further explained.

The spring device 3 is made of suitable metal and it has two bends 30—31 and it is 35 of suitable length and width for the purpose for which is provided. The upper bend 30 of the member 3 forms a hook for fitting the notch 10 in the upper edge of the lower base section 1 and 40 for flexibly clamping the upper section 2 over the upper part of the lower section 1, as is best shown in Figure 3. The other bend 31 of the device 3 terminates in an upturned hook 32 and the said bend 31 is of sufficient 45 length so that the hook 32 will receive the lower edge of the upper section 2, and in the finished product the said hook 32 is clamped over the said edge to aid in firmly holding 50 the long member of the spring device 3 and the top section to flex outwardly together 55 when the passed or matured month sheets are bent back and inserted in place between the contacting portions of the upper and lower sections 1 and 2 and for being engaged 60 by the tension clamp 31, as shown.

The date pad, that is, the pack of sheets 65 on which the consecutive monthly calendars are delineated are stapled along their upper edge in the usual way and the said pack or pads of sheets are attached along their up-

per back edge, by gluing or stapling to the lower base section 1, as indicated by 6 on Figure 3.

In my arrangement of calendar, the month sheets, when matured, that is, after the 70 months for which they are especially designed have passed, are not torn off as is usual, but are adapted for being bent back to preserve them for future reference, by tucking them under the spring portions 31 75 and between the opposing faces of the upper and lower base sections 1 and 2, as is clearly shown in Figures 2 and 3 of the drawings.

Each monthly calendar sheet, designated 80 7, is divided into squares and each sheet has the month, week and year designations arranged thereon in the usual manner.

Each date square, in my arrangement of monthly calendar sheets, has two small groups of supplemental figures, one group 85 70, in practice, being printed in red and the other of the said groups 71, printed in black, so that the different groups may be readily distinguished when reading the calendar.

The black figures 71 progressively increase 90 beginning with "1" on January 1st and ending with "365" on December 31st, while the red figures progressively increase in reverse direction, beginning with "1" December 31st of the year to 365, ending with January 1st 95 of the same year and to further facilitate the reading of the supplemental calendar numbers a division line 72 is run between the said supplemental figures, which figures together with the regular month dates, in 100 the preferred arrangement, are placed in vertical alignment, as is clearly shown in Figure 1 of the drawings.

Cooperative with the date pad, that is, the 105 pack of monthly sheets and the base formation with which the said sheets are used, as hereinbefore mentioned, is what is herein-after termed an instruction leaflet 8. The leaflet 8 is glued along the back of its upper edge 80 to the top or head portion of the pack or pad of monthly calendar sheets. The leaflet 8, before mentioned, is intended 110 as an attached or fixed part of the complete calendar and the said leaflet is tucked under the top section 2 and the spring device 3 115 when the calendar leaves the hands of the printer or other place where the said calendars are made up.

Normally the leaflet 8 is bent back, that 120 is, tucked under the upper base section 2 to expose the rear face thereof upon which certain instructions are printed which designate that the said leaflet is not to be torn away from the calendar pad, and that none of the parts of the pack or pad of monthly 125 calendar sheets are to be torn away, but that all of the said sheets, which constitute the pad or pack, are to be preserved for future reference, it being understood that as the monthly sheets mature they are individually 130

tucked back over the leaflet and over each other, and held to such conditions by slipping their loose or bottom ends between the base members 1 and 2 and the spring device 5 3, as before stated.

The leaflet 8 also has a notice thereon indicating that the other side of the leaflet has valuable instructions so that should one at any time desire to utilize the calendar as an 10 index reckoner by pulling the leaflet 8 down to expose its front face, explanation of the manner in which the calendar determines the dates when time in dates is given, or when exact time in days, between two dates, 15 is desired.

It will be noticed by referring to Figure 1 of the drawings, the calendar gives the exact time in days between two given dates, for example, should it be desired to learn the 20 number of days between August 8th to October 12th of the same year, the solution is as follows: August 8th is numbered in red "146" and October 12th is numbered in red "81". By subtracting the October number 25 from the August figure, the result is "65"—the answer.

This method of acquiring the desired data includes the last day mentioned but not the first. If both days mentioned, the 30 first and the last, are to be taken, then subtract 80 from 146 which leaves 66, as the correct answer.

How to determine dates when time in days is given is explained as follows:

35 *Problem.*

Work commenced on November 14th was promised in 95 days. At what date should it be completed?

40 *Solution.*

Days promised ----- 95
November 14th red number is -- 48
-----

45 By subtraction ----- 47

Look forward for the black number 47 found under February 16th, which is the date sought.

50 *Problem No. 2.*

Corn yielding in 90 days was planted June 22nd. At what date is it ready for harvest?

55 *Solution.*

Days required ----- 90
June 22d black number is --- 173

56 (By addition) ----- 263

60 Now look forward for small black number 263 found under September 20th, which is the date sought.

From the foregoing description taken in connection with the drawings, it will be seen 65 the pad sheets are so indexed that by reason

thereof any month desired for reference is at the fingers' ends, which avoids annoying and unnecessary paging, incident in the usual form of calendar pads, and consequent resultant in loss of time.

In my arrangement of monthly calendar sheets, the designating figures are so combined that a glance at any given date will disclose by the "black" figures, the number of days that have elapsed at the end of each date while the "red" figures indicate at the beginning of each date the days remaining for the year.

For instance, turning at random to August 8th, the "red" figures show that at 80 the beginning of such date, there are 146 days of the year remaining, while, on the other hand, the "black" figures indicate that at the end of the said date, August 8th, 220 85 days of the year have elapsed.

The leaflet 8, being an attached part of the calendar, as before stated, and which is tucked under the calendar base when the calendar is placed in use, the compilation of the figures on the various month calendar 90 sheets serve as a ready reckoner in determining days between given periods, therefore adapting itself as especially valuable for use by banks and insurance and business men in general where and whenever such computations, as before outlined, are required.

Figures 1 to 3 illustrate all of the month sheets of exact size and with their bottom edges in registering alignment and with the month indicating tabs arranged along one 100 edge, as is usual in calendar pads now in general use.

In Figure 5 is illustrated a modified and preferable construction of the month sheets or date pads which differs from the other form of date pad in that each sheet beginning with "February" is sufficiently longer than "January" to provide a bottom tab on which the "February" index is printed, "March" is likewise longer than "February" and "April" is similarly lengthened relatively to "March" and so on down to "December," it being understood that the monthly indicia on each sheet is printed or otherwise delineated on the said sheet and in consecutive lower relation, that is, the "February" calendar is relatively lower on its sheet than is "January" and "March" is lower than "February" and so on down to "December." The consecutive lowering of 110 the said calendar faces providing blank spaces at the top of each sheet, February having the minimum amount of blank space at the top and December the maximum amount, it being obvious that the increasing 120 blank area of the monthly sheets, the December space (owing to its size) will be relatively of the greatest value and the space on the February sheet of the minimum value for advertising purposes.

41
In the latter and preferred form of calendar pad, the monthly indexing is done downwardly by slightly lengthening the sheet of each succeeding month sufficiently to allow for the inscription of the name of the various months, as above mentioned.

What I claim is:

1. In a calendar of the character described, a base comprising an upper and a lower section, the lower end of the upper section lapping the upper end of the lower section, the said upper end of the lower section having a downwardly extending notch, a flat spring metal clamp having a turned back hook portion that fits within the notch and clamps over the upper end of the lower base section and which has a turned up flange at its lower end that clamps the lower edge of the upper base section, a date pad consisting of calendar sheets having the usual month and days of the month indicia thereon, the said pad of sheets having their upper ends attached to each other and to the base with their upper edge spaced from the lower edge of the overlapping top base section whereby provision is made for folding back the matured month sheets and tucking them between the overlapped portions of the upper and lower base sections and under the spring metal clamp.

2. In a calendar of the character described, a base comprising an upper and a lower section, the lower end of the upper section lapping the upper end of the lower section, the said upper end of the lower section having a 35 downwardly extending notch, a flat spring metal clamp having a turned back hook portion that fits within the notch and clamps over the upper end of the lower base section and which has a turned up flange at its 40 lower end that clamps the lower edge of the upper base section, a date pad consisting of calendar sheets having the usual month and days of the month indicia thereon, the said pad of sheets having their upper ends attached to each other and to the base with their upper edge spaced from the lower edge of the overlapping top base section whereby 45 provision is made for folding back the matured month sheets and tucking them between the overlapped portions of the upper and lower base sections and under the spring metal clamp, and a supplemental or direction sheet that is attached to the top edge of the pad of month sheets and is adapted for 50 being tucked under the lapped portions of the upper and lower base sections, the said supplemental sheet having explanatory indicia on its opposite side.

JOHN H. KULOW.
